UNITED STATES PATENT OFFICE

RENAULT COURTNEY ACUTT, OF GERMISTON, TRANSVAAL.

CIGAR AND CIGARETTE TUBE OR HOLDER.

1,001,725.

Specification of Letters Patent. Patented Aug. 29, 1911.

Application filed March 26, 1910. Serial No. 551,695.

To all whom it may concern:

Be it known that I, RENAULT COURTNEY ACUTT, a subject of the King of Great Britain, and resident of Germiston, Transvaal, have invented certain new and useful Improvements in Cigar and Cigarette Tubes or Holders, of which the following is a specification.

This invention relates to cigar and cigarette tubes or holders, and has for its object to construct a tube or holder from which the unconsumed end of the cigar or cigarette can be removed with greater facility than with tubes or holders as at present constructed. The removal of the unburned ends or portions of cigars and cigarettes from such tubes or holders, especially after the tubes or holders have been in use for a short time, usually necessitates the insertion 10 into the end of the tube or holder of a pin or other like means.

The object of this invention is to obviate this and to provide the tube or holder with a self-contained means for accomplishing 25 the purpose stated.

In accordance with this invention I construct the mouth piece with an extension which projects to a suitable point into the bore of the body or main part of the tube 30 or holder. Upon the mouth piece at the rear of the tube I provide a flange or its equivalent, and between said flange and the rear end of the tube I place a suitable spiral spring or equivalent resilient medium. 35 The portion of the mouth piece around which the spring is arranged is preferably inclosed by means of a ferrule, the rear end of which serves as a stop for limiting the movement of the mouth piece in a rearward 40 direction.

The invention will be more fully described by aid of the accompanying drawing in which—

Figure 1 is a longitudinal section of the 45 tube or holder showing the parts in their normal position. Fig. 2 is a view similar to Fig. 1 showing the position in which the parts are placed to remove the unburned end or portion of the cigar or cigarette, and 50 Fig. 3 is an elevation of the mouth piece detached.

All the views are drawn to an enlarged scale.

In the drawing 1 represents the mouth 55 piece of the tube or holder, and 2 the body

or main part of the tube or holder. Part 2 is constructed with a longitudinal hole 3 in which the extension or forward part 4 of the mouth piece fits and is adapted to slide longitudinally within certain limits. The bore 3 is tapered at the forward end as indicated at 5 for the reception of the end of the cigar or cigarette. At its rear end it is also counterbored or enlarged as at 6 for a purpose hereinafter explained. 60

The mouth piece 1 is constructed with a longitudinal hole or passage 7 and is fashioned at 8 with a flange or two or more projections. Encircling the mouth piece forward of the flange 8 is a suitable spiral 70 spring 9 which at one end bears against the bottom of the counterbore 6 and at the other end against the flange 8.

10 is a ferrule which serves for inclosing the spiral spring 9. The ferrule 10 is fixed 75 at one end in any convenient manner to the rear end of the tube 2, and at its rear end it is turned inward in the form of an inwardly directed flange 11 to serve as a stop against which flange 8 comes into contact to 80 limit the movement of the mouth piece 1 in a rearward direction.

The manner of operating the device will be readily understood on reference to Fig. 2. The mouth piece 1 is pressed forward 85 against the spring 9 until the forward end of the extension 4 assumes the position shown in Fig. 2. In assuming this position the unconsumed end of the cigar or cigarette is displaced or thrust out of the end of the 90 tube 2. On releasing the pressure the parts reassume their normal position as shown in Fig. 1.

What I claim as my invention and desire to protect by Letters Patent is:— 95

In a cigar or cigarette holder in combination a tube which is provided with a parallel bore for the greater portion of its length, said bore being counterbored at the rear end and made taper at the front end, a mouthpiece the front portion of which is parallel and constructed to slidingly fit the bore of the tube so that it can be moved longitudinally therein, said mouthpiece between the aforesaid parallel front portion and the 10 back rearwardly tapering portion being constructed with an annular projection which exceeds the diameter of the counterbore in the end of the tube, a helical spring which is placed around the mouthpiece between the 11

annular flange and the bottom of the counterbore and the rear end of the tube, and a ferrule fixed around the rear end of the tube, which ferrule serves for inclosing the helical spring and also as a stop which is engaged by the annular projection and limits the rearward movement of the mouth-piece, as set forth.

In testimony whereof I have signed my name to this specification in the presence of 10 two subscribing witnesses.

RENAULT COURTNEY ACUTT.
